UNITED STATES PATENT OFFICE.

SEBASTIAN STUTZ, OF PITTSBURG, PENNSYLVANIA.

COAL WASHING OR SEPARATING MACHINE.

SPECIFICATION forming part of Letters Patent No. 324,341, dated August 11, 1885.

Application filed December 10, 1884. (No model.)

To all whom it may concern:

Be it known that I, SEBASTIAN STUTZ, a citizen of the United States, residing at Pittsburgh, in the county of Allegheny and State of Pennsylvania, have invented or discovered certain new and useful Improvements in Coal Washing or Separating Machines, of which improvements the following is a specification.

In the accompanying drawings, which make part of this specification, Figure 1, Sheet 1, is a vertical transverse section through a coal-washing machine embodying my invention, at the line *xx* of Fig. 2; Fig. 2, a vertical longitudinal section through the same at the line *yy* of Fig. 1; Fig. 3, a transverse section, on an enlarged scale, through the delivery-bridge and upper portion of the coal-delivery compartment; Fig. 4, Sheet 2, a vertical transverse section through the elevator compartment; Fig. 5, a vertical longitudinal section through the same, and Fig. 6 a vertical central section through the piston, piston-rod guide, stuffing-box and buffer.

My present invention relates to coal-washing machines of the class which is exemplified in Letters Patent of the United States No. 188,691, granted and issued to me March 20, 1877, and reissued December 30, 1879, No. 9,011, and its object is to economise and facilitate the construction and operation of the machine by the provision of improved means for supporting the separator-box, with the capacity of ready access thereto, relieving the machine from shocks due to the impact of the piston, and guiding and regulating the length of stroke of the latter, and continuously removing the separated impurities without liability to waste by the escape of coal therewith.

The improvements claimed are hereinafter fully set forth.

In the practice of my invention I provide, as in my prior construction, a separator box or chest, 1, of substantially rectangular horizontal and vertical longitudinal section, which is preferably divided into two or more separate compartments, each fitted with the proper appliances to constitute a complete separating-machine independently of the others, all being, for convenience of operation within a desired degree of capacity, combined in a single structure. The three compartments

illustrated in the present instance, and the mechanism applied thereto, being similar in construction and operation, descriptive reference need be made herein to one compartment only, the description thereof being equally applicable to any of the three in the series.

Each of the compartments of the separating-box is divided by a curved partition, 3, into an upper separating or sieve chamber, 4, and a lower dead-water or sediment chamber, 5, and the separating-chamber 4 communicates by a lateral opening, governed by a valve or valves, 6, with a piston-chamber, 7, formed on the rear side of the compartment and extending downwardly thereon to or near the level of the partition 3. A sieve or screen, 8, extends across the compartment above the openings of the valves 6, and a series of slate-openings, 9, governed by valves 10, is formed in the front wall of the compartment, said openings establishing communication between the space above the sieve and a slate-compartment, 11, adjoining the front of the separating-box. The coal which is to be washed is supplied to each of the separating-chambers by a chute or feed channel, 22, having a hinged gate-board, 23, at bottom provided with regulating-arms 24, in order to cause the coal supplied to pass near the sieve 8 before reaching the delivery dam or bridge, as in my Letters Patent No. 198,432, dated December 18, 1877.

The several slate-compartments are separated one from the other by vertical partitions 12, which are open at bottom so as to provide thereat a chamber common to all the compartments 11, in which chamber a horizontal screw-conveyer, 13, is mounted in suitable bearings, and is adapted to be rotated from the driving-shaft 14 of the machine by a belt, 15, passing around a pulley, 16, on the driving-shaft, and a pulley, 17, on the conveyer-shaft. Fast and loose pulleys 18 19 are mounted on the driving-shaft 14 for the reception of a belt from the shaft of any suitable prime mover. A delivery-dam or horizontal bridge-piece, 20, extends along the front of the separating-box above the slate-openings 9, the discharge of the washed coal being effected over the top of said dam into a coal-delivery compartment, 21, common to all the compartments of the separating-box, and extending longitudinally in front of the slate-

compartments 11. An inclined partition extending from the top of the coal-delivery compartment at one end to or near the bottom at the opposite end, the position of which is indicated by dotted lines in Fig. 2, serves to carry the washed coal delivered over the dam 20 from the several compartments of the separating-box to a point at the bottom of the compartment 21, whence it may be removed 10 by an elevator or conveyer, or otherwise, as desired.

The sides of the separator-box are curved inwardly at bottom, as shown in Fig. 1, to reduce the volume of the sediment-chambers 5 to the proper limit, as well as to direct sediment that may pass into the chambers toward sediment-valves 25^a in the bottoms thereof, through which the deposited matter may be discharged from time to time, as required, and 15 the bottoms of the piston-chambers 7 are curved upwardly toward the rear of the chambers, in substantial correspondence with the curvature of the partition 3, to enable the proper action of the water upon the coal resting 20 on the sieves to be exerted with a less degree of power or a less weight of pistons than in former constructions.

The separating-box and piston-chambers rest upon and are supported by a series of 30 stout cast-iron standards, 25, each of which has a broad bearing-face on its top formed by lateral flanges extending continuously from the front of the slate-chamber, beneath the same and an adjacent sediment-chamber and 35 piston-chamber, to the rear of the latter, as shown in Figs. 1 and 2. The upwardly-curved members of the standards 25, which conform to the curvature of the rear sides of the sediment-chambers and bottoms of the piston- 40 chambers, which fit closely against and are supported by them, are connected at their rear ends by vertical members with the continuous horizontal members. In the construction of the machine the planking of the bottom 45 tons of the slate, sediment, and piston chambers and rear sides of the sediment-chambers is first laid in place on the top flanges of the standards and properly secured thereto, the standards serving primarily to enable the separating and piston-chambers to be formed and maintained in the desired shape in transverse section, and, further, to constitute the support 50 of the complete structure. The standards 25 are fixed upon suitable foundation-timbers, 26, 55 and clear space is thus afforded below the box for access to the lower portions thereof and to the sediment-valves, and for the location of other members presently to be described.

Water is supplied to the separator-box 60 through pipes 27, connected to the piston-chambers 7, and is, as in my former construction, forced through the coal resting upon the sieves 8 by the movements of box-shaped pistons 28, fitting in the chambers 7. The pistons 28 are secured upon piston-rods 29, to 65 which are connected cam-yokes 30 for the reception of cams 31, secured upon the driving-

shaft 14, the cam-yokes being, as in Reissue No. 9,011, before referred to, composed of four legs or standards connected by end heads or 70 sockets and located at such distance apart as to admit the cams 31 in one direction and the driving-shaft 14 in the other. The upper ends of the cam-yokes are secured to stems 32, fitting freely in fixed guides 33, and the yokes 75 are connected adjustably at their lower ends to the piston-rods 29 by couplings 34, which have the capacity of free rotation within the lower ends of the yokes, and are internally threaded to engage corresponding external 80 threads on the upper ends of the piston-rods. A series of square projections, 35, having radial slots or recesses 36, is formed on the couplings 34, and by the application of a wrench or bar to said projections or slots, as the case may 85 be, the position of the cam-yokes may be adjusted longitudinally so as to vary the stroke of the pistons within any desired range of the diameter of the cams, as the downward traverse of the pistons and rods is limited by buffers, 90 hereinafter described.

To insure the true rectilineal movement of the piston-rods, as well as to prevent the escape of water from the piston-chambers, long guides 37, through which the piston-rods pass freely, 95 are secured to the bottoms of the piston-chambers, said guides having stuffing-boxes 38 on their outer ends for the reception of packing, which is compressed therein by glands 39. The guides 37, in connection with the upper 100 guides, 33, prevent wear and friction of the pistons against the linings of their boxes and correspondingly promote the durability and easy working of the machine.

In order to relieve the machine from injurious strain and wear due to the impact of the pistons, the same is transmitted directly to the foundation through a buffer, 40, fixed thereon, and which may be packed with any suitable yielding or elastic material, said buffer 105 receiving the shock of the piston and rod on their descent when released by the cam, and thereby relieving the cam-shaft and separator-box from the repeated strains which would otherwise be induced upon them in operation. 110 The requisite elasticity of the buffer is in this instance provided for by the employment of a pair of stiff helical springs, 41, located within the buffer and covered by a follower, 42, fitting freely therein, said follower acting as an 115 abutment for a shoe, 43, secured upon the lower end of the piston-rod by a key, 44, or otherwise, so as to be readily removed and replaced by another when worn or broken by continued use.

These separated impurities which pass through the openings 9 into the slate-compartments 11 are carried therefrom by the conveyer 13 into an elevator-casing, 44, located adjacent to one end of the separator-box, and are thence delivered to a chute or other desired avenue of discharge by a vertical elevator composed of a pair of endless chains, 45, carrying a series 120 of elevator-buckets, 46, and passing around 125

5 polygonal-faced sprocket-wheels 47, fixed upon a shaft, 48, journaled in bearings adjacent to the bottom of the casing 44, and a pair of similar wheels, 49, secured upon a shaft, 50, mounted in bearings 51, above the top of the casing. The bearings 51 are fitted with the capacity of vertical adjustment in recesses formed in standards 52, secured upon the top of the casing 44, and may be adjusted therein 15 to maintain the requisite degree of tightness of the chains by screws 53, engaging female threads in the standards and abutting against the lower sides of the bearings 51. The elevator is actuated by a belt, 54, passing around a pulley, 55, on the upper elevator-shaft, 50, and around a pulley on the driving-shaft 14, (indicated in dotted lines in Fig. 1.) A pair of inclined discharge-plates, 56, is secured between the sprocket-wheels 49 in such position 20 relatively to the shaft 50 that in the rotation of the latter one of said plates will immediately precede each of the buckets in its traverse around the shaft, and will thereby direct and deliver the material discharged from the buckets into a proper chute or receiver, and prevent it from falling back into the casing as the buckets successively change their direction of movement in the traverse of the chain. 25

30 It will be seen that by the construction above described the discharge of the separated impurities is continuously and automatically effected, and the possibility of their accumulation in the compartments 11, which 35 might occur by carelessness of the attendant in the machine of prior constructions, is wholly prevented. The area of delivery through the openings 9 may be varied and accurately adjusted, as required by the character of the 40 material treated, by means of a lever, 57, secured to a shaft, 58, mounted in bearings on the top of the separator-box, said shaft carrying arms 59, coupled by links 60 to the valves 10, and having a slotted arm, 61, through 45 which the shaft may be fixed in position to maintain any desired degree of opening of the valves 10 by a set-screw, 62, passing through the slot of the arm 61.

I claim herein as my invention—

50 1. In a coal-washing machine, the combination of a separator box or chest having a slate-chamber on one of its sides and a piston-chamber on the other, and a series of standards having horizontal members adapted to 55 rest upon a suitable foundation and bearing-surfaces on their upper sides extending continuously beneath and fitting against the bottoms of the slate, sediment, and piston-chambers and the side of the sediment-chamber 60 which adjoins the piston-chamber, substantially as set forth.

2. In a coal-washing machine, the combination of a separator-box, a piston-chamber connected therewith, a piston fitting said chamber, a piston-rod secured to said piston, a 65 stuffing-box located in the bottom of the chamber, through which said piston-rod passes, a

series of supporting-standards resting upon a foundation and having bearing-surfaces on their upper sides extending continuously beneath and fitting against the bottoms of the separator-box and piston-chamber, and a buffer fixed to a foundation below the piston-chamber in line with the piston-rod, substantially as set forth. 70

3. In a coal-washing machine, the combination of a separator-box, a lateral piston-chamber, a piston-rod carrying a piston fitting said chamber, a guide fitting the piston-rod above said chamber, a guide fitting the piston-rod 80 and fixed in the bottom of the chamber, and a stuffing-box located at the outer end of said bottom guide, substantially as set forth.

4. In a coal-washing machine, the combination of a separator-box, a lateral piston-chamber, a piston fitting said chamber, a piston-rod secured to said piston and passing through the bottom of the chamber, a removable shoe connected to the lower end of the piston-rod, and a buffer fixed to a foundation below and in 90 line with the rod, substantially as set forth.

5. In a coal-washing machine, the combination of a separator-box, a slate-chamber, a conveyer adapted to rotate adjacent to the bottom of the slate-chamber, an elevator casing communicating with the delivery end of the conveyer, an independent elevator working in said casing, and driving pulleys or gears for operating said elevator independently of the conveyer, substantially as set forth. 95

6. In a coal-washing machine, the combination of a separator-chamber, a slate-chamber, an elevator-casing communicating with the slate-chamber, an elevator working in said casing, and a series of discharge-plates fitted 105 to rotate with the upper sprocket-wheels of the elevator, substantially as set forth.

7. In a coal-washing-machine, the combination of a piston-chamber, a piston fitting said chamber, a piston-rod secured to the piston 110 and extending above and below the same, a lifting-yoke secured to the upper end of the piston-rod, a cam working said lifting-yoke, and a buffer fixed to a foundation below the piston-chamber and in line with the piston-rod, substantially as set forth. 115

8. In a coal-washing-machine, the combination of a series of separating-chambers, a series of communicating slate-chambers, a conveyer common to the series of slate-chambers 120 and adapted to rotate adjacent to the bottom thereof, an elevator-casing into which said conveyer discharges, an independent elevator working in said casing, and driving pulleys or gears for operating said elevator independently of the conveyer, substantially as 125 set forth.

In testimony whereof I have hereunto set my hand.

SEBASTIAN STUTZ.
